The ornamental design for a sanding glove, as shown and described.

DESCRIPTION

FIG. 1 is a perspective rear view of a sanding glove, showing my new design;

FIG. 2 is a perspective front view thereof;

FIG. 3 is a rear view thereof;

FIG. 4 is a front view thereof;

FIG. 5 is a left side view thereof;

FIG. 6 is a right side view thereof;

FIG. 7 is a top view thereof; and,

FIG. 8 is a bottom view thereof.

The stipple surface shading of the sanding glove shown in FIGS. 1 through 8 illustrates a coarse surface texture.

FIGS. 1 through 8 illustrate a right hand sanding glove of the present invention, but it is to be understood that this invention also includes a left hand sanding glove that is the same as the glove illustrated in FIGS. 1 through 8 respectively except being a mirror image thereof.
